ROTARY EXPLOSIVE-ENGINE.

1,309,096.

Specification of Letters Patent.

Patented July 8, 1919.

Application filed December 14, 1917. Serial No. 207,032.

To all whom it may concern:

Be it known that I, WILLIAM E. LEIBING, a citizen of the United States, residing at Oakland, in the county of Alameda and 5 State of California, have invented certain new and useful Improvements in Rotary Explosive-Engines, of which the following is a specification.

The present invention relates to rotary 10 engines of the internal combustion type.

The object of the invention is to provide, in such an engine, means for positively operating the valves or abutments, to cause them to closely follow the surface of the 15 rotating piston, even at very high speeds. It has been found in practice that such valves cannot be successfully operated by means of springs, for the reason that, on account of the necessary weight of the parts and the 20 speed at which they must operate, their inertia cannot be overcome in the requisite period of time by springs, and that therefore the valves do not properly follow the piston.

25 With this and other objects in view, the invention will be hereinafter described in its preferred form, but it is to be understood that changes, within the scope of the claims hereto appended, may be made in the form 30 and construction of the machine without departing from the spirit of the invention.

In order to more fully comprehend the invention, reference should be had to the accompanying sheets of drawings, wherein—

35 Figure 1 is a side elevation of my rotary engine.

Fig. 2 is a side elevation, with one side plate removed, showing the interior of the cylinder and the piston and valves therein.

40 Fig. 3 is a sectional plan view taken on the line 3—3 of Fig. 2, and viewed in the direction of the arrows.

Fig. 4 is a sectional detail, enlarged, of the by-pass and valve therefor.

45 Fig. 5 is a sectional detail, enlarged, of a portion of one of the valves, showing the metal packing member in the side edge thereof.

In the drawings, the reference numeral 1 50 designates the cylinder of the engine, the same being preferably composed of a peripheral ring portion 2, and side cover plates 3 and 4, said three parts being suitably secured together, and supported by a base 5.

A rotor 6 is mounted within said cylinder 1, 55 upon a shaft 7 passing centrally through said side plates 3 and 4, and being suitably journaled therein, as shown at 8 in Fig. 3 of the drawings.

The rotor 6, which is of a width sufficient to fill the cylinder 1 axially, has a radial piston portion 9, Fig. 2 of the drawings, adapted to travel in close relation to the inner surface of the peripheral cylinder wall 2. Swinging abutments or valves 10^a, 60 10^b, 10^c and 10^d, carried by transversely disposed shafts 11^a, 11^b, 11^c and 11^d respectively, are adapted to lie against and follow closely the peripheral surface of the rotor 6. As shown in Fig. 2 of the drawings, pockets 70 12^a, 12^b, 12^c, and 12^d are formed in the peripheral cylinder wall 2, within which the respective valves 10^a, 10^b, 10^c and 10^d may retreat to permit passage of the piston 9, and to form a smooth surface upon which 75 said piston rides. Said valves, as shown in Fig. 3 of the drawings, are the full width of the cylinder, and are provided with metallic packing members 13 in their side edges. Said packing members are preferably 80 formed of flat strips of metal, set into a groove formed in the edge of the valve, and slotted as shown at 14 in Fig. 5, to provide the necessary resiliency.

The valves are operated by means of cams 85 15^a, 15^c and 15^{bd}, Fig. 3 of the drawings, fixed to the projecting ends of the rotor shaft 7. The cams 15^a and 15^c, Figs. 1 and 3, positioned adjacent each other upon one end of said shaft, respectively operate the 90 valves 10^a and 10^c by means of tappets 16^a and 16^c, slidably carried in suitable lugs or brackets 17^a and 17^c extending from the cylinder wall 3. Rollers 18^a and 18^c are preferably provided in the ends of said tappets 95 to follow said cams. The other ends of said tappets carry adjusting screws 19^a and 19^c, whose heads are adapted to bear against and actuate lever arms 20^a and 20^c, extending from the valve shafts 11^a and 11^c respectively. A spring 21^a, surrounds the tappet 16^a, and acts thereupon in the same direction as the cam 15^a, that is to hold the valve 10^a in contact with the surface of the rotor 6. It is to be noted that the valve 10^a is held in 105 contact with the surface of the rotor 6 by its cam 15^a, a depression 22^a in the surface of said cam permitting said valve to ride over

the piston 9, whereas the valve 10^c is moved out of contact with the rotor surface by its cam 15^c, the low portion 22^c of said cam permitting said valve to move against said 5 rotor surface. Said valve 10^c, when held away from the rotor surface by its cam 15^c, closes a combustion chamber 23, Fig. 2, an adjustable seat 24 being provided to insure the correct positioning of said valve under 10 such conditions.

The cam 15^{bd}, Figs. 2 and 3 of the drawings, mounted on the shaft 7 on the opposite side of the cylinder from the cams 15^a and 15^c, operates both the valves 10^b and 10^d, by 15 means of tappets 16^b and 16^d respectively, slidably journaled in lugs 17^b and 17^d, and provided with cam following rollers 18^b and 18^d, and adjusting screws 19^b and 19^d, the latter bearing against lever arms 20^b and 20^d 20 extending from the valve shafts 11^b and 11^d. Both of said tappets are provided with springs 21^b and 21^d, respectively, acting in the same direction as the cam.

The valves 10^b and 10^d are thus held in 25 contact with the rotor surface by the cam 15^{bd}, the depression 22^{bd} therein permitting said valves to ride over the piston 9. In this connection it should be stated that the function of the springs 21^a, 21^b and 21^d, surrounding their respective tappets, is merely to hold the valves 10^a, 10^b and 10^d in close contact with the rotor surface, even in the event of some looseness or play between the cam and the valve. Said springs are not relied 30 upon for moving the valves inwardly after the passage of the piston 9, this movement being positively accomplished by the cams.

A by-pass 25, Fig. 4 of the drawings, is provided around the valve 10^b, for conducting 40 gas from the upper portion of the cylinder into the combustion chamber 23. Said by-pass is controlled by a check valve 26, held to its seat by a spring 27, said spring acting against the stem 28 of said check 45 valve, within a suitable guide member 29. The check valve, as will be readily understood, prevents the gas from passing back into the upper portion of the cylinder. Apertures 30 are provided in said combustion 50 chamber 23, through which the gas therein may be fired by any well known means, not shown in the drawings, as, for example, a spark plug of the common type.

The operation of the engine may be described as follows:—

Assuming that the rotor 6 rotates in the direction of the arrow in Fig. 2 of the drawings, after the piston 9 has passed the valve 10^a, and during the travel thereof from said 60 valve 10^a to the valve 10^b, a charge of unburned gas is drawn in to the upper portion of the cylinder 1 through a carburetor indicated at 31, in Fig. 1, and an intake passage 32. During this travel of the piston 9, the 65 valve 10^a is held in contact with the rotor

surface by its cam 15^a, thus cutting off the upper portion of the cylinder 1 from the lower portion thereof, and after the piston has passed the valve 10^b the charge of raw gas is entrained within the upper portion of 70 the cylinder 1, remaining therein during the next half revolution of the rotor. When the piston 9 again passes the valve 10^a, and begins to draw in a second new charge, the first charge of gas contained within the 75 upper portion of the cylinder 1 is compressed by the advancing piston 9, and is forced through the check valve 26 and the by-pass 25 into the combustion chamber 23, the valve 10^b being held to its seat 24 by its 80 cam 15^c.

The first charge of unburned gas is now compressed within the combustion chamber 23, being retained therein by the check valve 26 and the cam actuated valve 10^c.

Immediately after the piston passes the valve 10^c, the charge within the combustion chamber 23 is ignited, by any means not shown in the drawings, and the expansion thereof causes the valve 10^c to open and to 90 lie closely along the rotor surface behind the piston 9; and the pressure of this gas on the rear of said piston 9, causes the same to travel in the direction of the arrow toward the valve 10^d, thus imparting a power impulse to the rotor. When said valve 10^d is reached by said piston, an exhaust port 33 is uncovered, and the remaining burned gases are allowed to exhaust therethrough. Upon the next revolution of the rotor, the 95 lower portion of the cylinder 1 is scavenged of the spent gases of the first charge by the advancing piston 9 during its second power stroke. Thus, it requires three revolutions of the rotor to complete one cycle of operation, the admission occurring on the first 100 revolution, the compression and expansion on the second, and the exhaust on the third; but on account of the overlapping of the cycles, a new cycle is begun at every revolution, so that one power impulse occurs during every revolution.

Having thus described my invention, what I claim as new and desire to protect by Letters Patent is:—

1. A rotary engine comprising a cylinder, a shaft rotatably and axially mounted with respect to said cylinder, a rotor carried by said shaft within said cylinder, a radial piston carried by said rotor, means for admitting gas to said cylinder and discharging the same therefrom, a pair of valves adapted to coact with said rotor and said piston to form a suction and compression chamber in the upper portion of said cylinder, another pair of valves adapted to coact with said rotor to form an expansion and exhaust chamber in the lower portion of said cylinder, means for controlling the transference of the compressed gas from the upper 110

to the lower portions of said cylinder, and mechanism actuated by said rotor for operating said valves.

2. A rotary engine comprising a cylinder, .5 a shaft rotatably and axially mounted with respect to said cylinder, a rotor carried by said shaft within said cylinder, a radial piston carried by said rotor, means for admitting gas to said cylinder and discharging 10 the same therefrom, a pair of valves adapted to co-act with said rotor and said piston to form a suction and compression chamber in the upper portion of said cylinder, another 15 pair of valves adapted to co-act with said rotor to form an expansion and exhaust chamber in the lower portion of said cylinder, and said cylinder having a by-pass between said upper and lower portions, a 20 check-valve in said by-pass, and means actuated by said rotor for actuating the valves co-acting with said rotor.

3. A rotary engine comprising a cylinder having a gas inlet opening in its upper portion, a gas outlet opening in its lower portion; and a combustion chamber between 25

said upper and lower portions, a rotor within said cylinder, a radial piston carried by said rotor, a pair of valves co-acting with said rotor to form a suction and compression chamber in the upper portion of said cylinder, mechanism for causing said valves to maintain positive contact with the rotor surface, a check-valve for permitting gas to pass into said combustion chamber from the upper portion of said cylinder, a second pair 30 of valves coacting with said piston to form an expansion and exhaust chamber in the lower portion of said cylinder, and mechanism actuated by said rotor to cause one of the last mentioned valves to close said combustion chamber from said lower cylinder portion during the compression of the gas in the former.

In testimony whereof I have signed my name to this specification in the presence of 45 two subscribing witnesses.
